UNITED STATES PATENT OFFICE

JOSEPH H. MORROW, OF CATASSAUQUA, PENNSYLVANIA, ASSIGNOR TO FULLER COMPANY, A CORPORATION OF PENNSYLVANIA

PORTABLE PUMP

Application filed August 15, 1928. Serial No. 299,718.

This invention relates to the conveying of pulverized or finely divided materials such as cement, soda ash, lime, etc., and more particularly to a conveying apparatus for handling such materials when stored loosely in bulk. It is especially applicable to the unloading of materials from box cars and barges and to the removal to other points of materials stored in open bins.

- 10 The invention is particularly directed to certain improvements and modifications of the apparatus shown and described in Kinnyon Patents Nos. 1,553,539, issued September 15th, 1925; 1,652,281 issued December 15th, 1927; and 1,677,119, issued July 10th, 1928. As described in the patents referred to, the materials to be conveyed are rendered fluent in the Kinnyon apparatus by the injection of a small quantity of compressed air 20 or other gas and are then forced through pipe lines of extended length by the mechanical pressure of an impeller screw or other conveyor, the normal expansion of the air being used to create the fluent condition.
- 25 The conveyor itself, commonly referred to as a pump, consists essentially of a hollow casing having an inlet hopper to which the materials are delivered continuously from a storage bin, pulverizer or other source.
- 30 Within the hopper an impeller screw rotates and advances the material to a point where air is admitted. The primary function of this air is to destroy internal friction in the mass of material so that the latter may be forced through a pipe line by the mechanical pressure of the screw and the normal expansion of the air. In this aerated condition each particle of material seems to be surrounded by a thin film of air which destroys 35 internal friction in the mass and friction against the walls of the transport pipe line; the material is expanded to approximately twice its normal volume and although it is apparently a solid it has many of the characteristics of a liquid and will flow through the pipe line under the pressure of the screw and the advancing material column.

In order for the apparatus to operate at maximum efficiency, it is necessary to prevent aeration of the material as it is ad-

vanced along the screw itself, as the decreased friction would cause the screw to slip and the increased bulk would decrease the total quantity, by weight, actually delivered from the system.

This premature aeration is prevented by subjecting the material to continuously increasing pressure as it is advanced through the casing to the point of air admission, to form a densely compacted mass of material through which air cannot penetrate. This may be accomplished by a number of arrangements, for example, a differential pitch screw having flights of constant diameter and decreasing pitch toward the discharge end may 55 be used, or a portion of the casing may be formed as a truncated cone discharging toward its shorter end, or by using a conical screw the material will be compacted. Another alternative consists in using a screw 60 of constant pitch and diameter the flights of which terminate a sufficient distance from the point of air admission to form the densely compacted mass of material due to the pressure of the advancing material and friction 65 against the walls of the casing. As local conditions, such as the length of the system, number of bins, elevations, etc., govern the static resistance of the conveying system and as material density may also be a local condition, 70 the most usual commercial practice is to use a screw of constant diameter and decreasing pitch, the flights terminating a short distance from the point of air admission to form a short dead seal space. By combining with 75 either a conical or differentially pitched screw, a dead seal space, as described above, the density and consequently the friction may be kept at a minimum and a greater latitude is permitted as the dead space may be 80 increased or decreased by cutting away a part of the terminal flight or by adding to it. This dead seal space rarely exceeds 3 inches in 85 length.

It is not an object of my invention to modify particularly the method of operation of the apparatus of the patents but to modify the structure in order that the device will be readily portable and can be handled by one man.

The new apparatus is arranged to be moved into a mass of material which is introduced and advanced through a casing by a rapidly rotating screw. Slightly beyond the screw and in the zone of greatest material density, compressed air is admitted preferably through a plurality of small openings surrounding the screw shaft. The shaft extends through a wall of the casing through which additional air is admitted to form a counter current to prevent abrasive dust from working along the shaft and into the bearing surfaces and driving motor. This air, reacting against the air admitted through the apparatus referred to, increases the fluency of the material conveyed. The casing terminates in the form of an angular discharge elbow which, if the apparatus is to be used as a portable conveyor, is connected to a length of flexible hose, such as the stiff-walled hose for liquid suction pumps. This hose may in turn be connected to the usual steel pipe line leading to the various points of delivery.

In order to decrease the weight, simplify the apparatus and facilitate repairs, the motor and screw have a common shaft and shaft bearings. When used for unloading box cars or flat bottom bins the apparatus is mounted on wheels, the axle shaft of which is secured slightly to the rear of the center of weight so that the apparatus will have a tendency to tip forwardly. Suitable handle bars are provided so that the device can be pushed into a pile of material. When unloading full bins or barges the wheels may be removed and the apparatus suspended from cables.

This invention has the advantage of the large capacity and low power and maintenance cost of the Kinyon apparatus as described above, and likewise is lacking in mechanical and fire hazard.

For a better understanding of the invention, reference will be made to the accompanying drawings in which:

- 45 Fig. 1 is a sectional elevation,
- Fig. 2 is a detail of the air admission apparatus,
- Fig. 3 is a transverse section on line 3—3 of Fig. 2,
- 50 Fig. 4 is an enlarged detail in section of the shaft and bearing assembly on line 4—4 of Fig. 1,
- Fig. 5 is a rear view of the apparatus, showing the supports.

Referring now to the drawings, the apparatus is shown to consist of a barrel or casing 10, having a cylindrical forward section 11, open at its forward end, and a rearward 60 conical section 12, suitably bolted or otherwise secured as at 13, to the offset discharge section or elbow 14. The discharge elbow terminates in a suitable coupling 15 for the flexible rubber hose 16. The forward end 11 of the casing 10 may be secured to a remov-

able scoop 17 or may be secured directly to a bin spout.

The material to be conveyed is picked up by the screw 18 secured to a shaft 19, mounted for rotation in suitable bearings as will be described hereinafter. In order to handle a maximum quantity of material and to effect the dense seal of material as described above, in the shortest space, the forward flights such as 20 and 21 are of relatively larger diameter than the flights 22 in the conical section of the casing 12. The terminal flight 23 is of the least diameter and terminates a short distance from the point of air admission to form a dead seal space.

The shaft 19 tapers toward the inlet end of the casing to decrease the tendency for the shaft to oscillate and to decrease the total space progressively within the casing in order to increase the density of the material conveyed. As shown in detail in Fig. 2, a recess is formed at 23' in the flange 24 of the conical section 12. This recess accommodates an annular boss 25 in the flange 26 of the discharge elbow 14. This arrangement together with the usual gasket (not shown), prevents the escape of compressed air to the atmosphere. Flanges 24 and 25 are again recessed to form an annular channel 27 into which air is admitted through the inlet 28. The inner side of the channel 27 is closed by an air ring 29 secured in recesses 30 and 31 of the flanges 24 and 26 respectively. This air ring 29 has a groove 32 formed on its outer surface which communicates with the channel 27. An annular inclined shoulder 33 is formed on the inner surface and air ports 38, extending approximately at right angles to the shoulder communicate with the groove 32 to admit air into the material at the zone of greatest density.

The air ports 38 extend in a radial direction excepting that their inclination to the axis of the ring is greater at the bottom of the ring, for in the device shown the discharge elbow 14 extends upwardly. If the device is arranged to discharge downwardly, the air ring should be inverted. This arrangement produces a more uniform aeration and overcomes the natural tendency of material to move downwardly.

Air is admitted to the channel 27 through a piping system 39 under control of a suitable valve 40. The air is conducted to the valve through the usual flexible rubber hose (not shown). T 41, reducer 42 and the small pipe line 43, serve to by-pass a small quantity of air for excluding dust from the bearing surfaces as will be described hereinafter.

At the lowermost portion of the air channel 27, an outlet 44 communicates with elbow 45 and valve 46. This valve is normally closed and is provided to enable the operator to blow the channel clear of material which may accumulate therein when the apparatus is idle.

The drive arrangement can best be understood by reference to Figures 1 and 4. The shaft 19 passes through the housing 47 cast as an integral part of the discharge elbow.

5 The motor and bearing assembly is suitably bolted or otherwise secured to the housing 47 as shown at 48.

The stator frame 50 of the motor is secured to the motor end bells 51 and 52 by bolts 53.

10 The end bells are provided with the usual supports or webs 54 and 55 to support the forward bearing housing 56 and the rear bearing housing 57. The spaces between the supports or webs 54 are closed by sheet metal covers

15 58 to exclude dust from the motor. The spaces between the rear webs 55 are left open to allow for the circulation of air to cool the motor.

The shaft 19 is reduced in diameter at 60

20 and is surrounded by the motor rotor bushing 61, the rotor being keyed to the bushing at 62 (see Fig. 1) within the bearing housing 57. The shaft and rotor bushing are supported in a combined radial and thrust ball bearing 63, the races of which are recessed into the rotor bushing 64 and into the thrust collar 65 at 66. The end of the shaft is reduced and threaded and the shaft and thrust collar are secured by a nut 67. Cap 68 excludes dust from the bearing.

The front radial ball bearing includes an outer race 69 secured in a recess in the bearing housing 56 by bearing cover 70. The inner race 71 surrounds the rotor bushing 61 which is reduced in diameter to accommodate the bearing race, and is secured in place by bearing retaining ring 72 screwed or otherwise secured to the rotor bushing. Bearing housing 70 is provided with the usual grease packing 73 to prevent grease from working forwardly along the bushing.

In order to form a counter current of air along the shaft 19, air from the small pipe line 43 enters the housing 47 through inlet

45 74 communicating with an inlet in an air seal housing 75. A channel 76 formed in the inner surface of the air seal housing surrounds rotor bushing 61 and permits the air to escape forwardly. The air is distributed

50 in equal pressure and volume by means of a labyrinth collar 77 screwed or otherwise secured to the rotor bushing. The air is thus evenly distributed and moves forwardly along the shaft 19 through a narrow space 78 55 between the shaft and the wall of the housing 47.

The air is prevented from escaping rearwardly toward the bearings by packing rings 79 which are held in place by a spring 80 and retaining rings 81. The packing 79, spring 80 and retaining rings 81 are held in place by the plate 82 which is screwed on its outer edge to the air seal housing 75.

As shown in Fig. 5, the device is supported on wheels 83 and 84, mounted for rotation

to the axle shaft 85. The axle shaft is flattened, as shown at 86 in Fig. 1 and is curved to accommodate the stator frame 50 of the motor, the shaft preferably surrounding the lower half of the motor. The device is 70 also secured by a cross-member 87, bolted at 88 to the stator frame 50 and suitably secured to the handle bars 89 and 90. It will be seen that the center of support of the entire apparatus is slightly to the rear of the 75 center of weight, in order that the conveyor will tend to tilt forwardly to facilitate entry into the material to be transported.

In order to reduce the total weight of the apparatus many of the parts may be made of 80 a light material such as aluminum. For example, the motor end bells 51 and 52, the casing 10 and the discharge elbow 14, may be made of aluminum, although if an abrasive material such as cement is to be handled, 85 the casing 10 should be made of cast-iron or steel. The screw flights, being subject to the greatest wear, as well as the inner surface of the air ring 29 should be protected by a thin layer of wear resisting metal such as the alloy 90 commonly known as "Stellite". The screw flights themselves are preferably made of half sections of cast-steel.

The operation and device is as follows:

Air is admitted through the valve 40 and 95 discharges into the casing and discharge elbow through the air ring 29 and around the shaft 19 where it passes through the wall of the elbow. Valve 46 is then opened momentarily to blow the air channel 27 free of 100 dust in order to prevent plugging of the inlets 38. The driving motor is then started and the conveyor can then be moved into the pile of material to be conveyed or the scoop 105 17 may be disconnected and the casing section 11 secured to a bin spout.

It will be apparent that by means of the common motor and shaft bearings the apparatus is relatively light in weight, simple in construction, and at the same time alignment difficulties are avoided. As the screw itself is subject to the greatest wear and must be repaired more often than any other element of the device, the rotor bushing has been provided in order to avoid replacement of the 110 air sealing and bearing elements when the screw must be renewed. In accordance with the present design the removal of the nut 67 and its cooperating thrust collar 65 together with key 62, makes it possible to substitute a new screw shaft or to make repairs quickly.

In the preferred form of my invention, illustrated and described above, the discharge of the apparatus is upward in order 125 that the wheels may carry a portion of the weight of the flexible hose as well as the air hose for supplying the apparatus. In addition, the specific form of screw shown has the advantage of large flights for entering the 130

pile of material in order to remove a maximum quantity, and in cooperation with the conical screw section the seal of material to resist the tendency of the air to discharge 5 forwardly can be made in the shortest space. It is to be understood that the invention is not limited to the type of screw shown nor to the upwardly directed discharge elbow.

What is claimed is:—

10. 1. Apparatus for conveying pulverized material comprising a casing having an open end for the admission of material, an offset discharge elbow connected to the other end of the casing, a screw shaft within the casing 15 and extending through a wall of the discharge elbow, a bushing surrounding the shaft and secured thereto beyond the elbow, the bushing being supported in spaced bearings and driving means secured to the bushing 20 between the bearings.

2. Portable apparatus for conveying pulverized material through a pipe line comprising the combination of a casing having an open end for the admission of material, 25 an offset discharge elbow connected to the other end of the casing, a screw shaft within the casing and extending through a wall of the elbow and mounted in spaced bearings therebeyond, a rotor of a motor secured to 30 the shaft between the bearings, a stator frame surrounding the rotor, and a pair of wheels mounted on axles secured to the stator frame slightly to the rear of the center of weight 35 of the apparatus in order to cause the apparatus to tilt forwardly.

3. Apparatus for conveying pulverulent material, which comprises the combination of a casing having an opening at one end for the admission of material and an opening at 40 the other end for discharge thereof, a shaft having a portion lying within the casing, said portion being provided with a conveyor screw, a motor having a frame attached to the casing near one end thereof, the rotor 45 of the motor being connected to the shaft, a rolling support attached to the frame, the weight of the motor, casing and associated parts being transmitted to the support through the frame, and spaced bearings in 50 the frame for supporting the shaft, said bearings lying at opposite ends of said rotor.

4. Apparatus for conveying pulverulent material, which comprises the combination of a casing having an opening at one end for the admission of material and an opening at 55 the other end for discharge thereof, a shaft having a portion within the casing, said portion being provided with a conveyor screw, a motor having a frame attached to the casing, the rotor of said motor being mounted on the shaft, spaced bearings carried by the frame for supporting the shaft, said bearings lying one at each side of the rotor and the bearing at the end of the shaft remote 60 from the casing being a thrust bearing, a

rolling support for the frame adapted to carry the weight of the motor, casing and associated parts, means for introducing air into the casing near the discharge end thereof, and means for introducing air into the casing along said shaft, the air flowing along the shaft preventing the ingress of materials being conveyed into the adjacent bearing. 70

5. Apparatus for conveying pulverulent material, which comprises the combination of a casing having an opening at one end for the admission of material and an opening at the other end for discharge thereof, a shaft having a portion within the casing, said portion being provided with a conveyor screw, a motor having a frame attached to the casing, 75 a bushing on the shaft connected thereto, the rotor of said motor being mounted rigidly on the bushing, a rolling support attached to the frame and carrying the weight of the motor, casing and associated parts, and spaced bearings mounted in the frame for supporting said bushing and shaft. 80

6. Apparatus for conveying pulverulent material, which comprises the combination of a casing having an opening at one end for the admission of material and an opening at the other end for discharge thereof, a shaft having a portion within the casing, said portion being provided with a conveyor screw, a motor having a frame attached to the casing, 90 the rotor of said motor being connected to the shaft, spaced bearings for the shaft, one on each side of the rotor, said bearings being mounted in the frame, with the bearing remote from the casing adapted to place the shaft under tension in the operation of the device, and a rolling support attached to the frame and supporting the weight of the motor, casing and associated parts transmitted through the frame to the support. 95

7. Apparatus for conveying pulverulent material through a pipe line comprising the combination of a casing having an opening at one end for the admission of material, an offset discharge elbow connected to the other end of the casing, a screw shaft within the casing extending through the wall of the elbow and mounted in spaced bearings beyond said elbow, a rotor of a motor attached to the shaft between the bearings, a stator frame surrounding said rotor, said stator frame being rigidly attached to the casing, and a rolling support attached to the frame for bearing the weight of the motor, casing and associated parts transmitted to the support through the frame. 110

8. Apparatus for conveying pulverulent material which comprises the combination of a casing having an opening at one end for the admission of material, an elbow discharge section connected to the casing at the other end, means for admitting air into the discharge section adjacent the end of the casing, a shaft extending through the wall of 115 the casing being a thrust bearing, a

the section into the casing and carrying a screw for advancing material through the casing and out through the section, a quill surrounding the shaft beyond the wall of the casing, and a motor having a rotor mounted on said quill and a stator rigidly secured to the section.

- 6 9. Apparatus for conveying pulverulent material comprising a casing having an open end for the admission of material, an offset discharge elbow connected to the other end of the casing, a screw shaft within the casing and extending through the wall of the discharge elbow, a bushing surrounding the shaft, the bushing being supported in spaced inner and outer bearings, driving means secured to the bushing between the bearings, the shaft being secured to the bushing by locking means beyond the outer bearing.
- 10 10. Apparatus for conveying pulverulent material comprising a casing having an open end for the admission of material, an offset discharge elbow connected to the other end of the casing, a screw shaft within the casing and extending through the wall of the discharge elbow, a bushing surrounding the shaft beyond the elbow, the bushing being supported in spaced bearings, the bearing adjacent to the discharge elbow being a radial bearing, the bearing remote from the discharge elbow being a combined thrust and radial bearing, driving means secured to the bushing between the bearings and means beyond the thrust bearing for securing the screw shaft to the bushing.

11. Apparatus for conveying pulverulent material which comprises the combination of a casing having an opening at one end for the admission of material and an opening on the other end for the discharge thereof, a shaft having a portion within the casing, said portion being provided with a conveyor screw, a motor having a frame attached to the casing, the rotor of the motor being mounted on the shaft, spaced bearings carried by the frame for supporting the shaft, the said bearings lying one at each side of the rotor, means for introducing air into the casing near the discharge end thereof, and means for introducing air into the casing along said shaft, the air flowing along the shaft to prevent the ingress of materials being conveyed into the adjacent bearing.

12. Apparatus for conveying pulverulent material which comprises the combination of a casing having an opening at one end for the admission of material and an opening on the other end for the discharge thereof, a shaft having a portion within the casing, said portion being provided with a conveyor screw, a motor having a frame attached to the casing, the rotor of the motor being mounted on the shaft, spaced bearings carried by the frame for supporting the shaft, the said bearings lying one at each side of

the rotor and the bearing at the end of the shaft remote from the casing being a thrust bearing, means for introducing air into the casing near the discharge end thereof, and means for introducing air into the casing along said shaft, the air flowing along the shaft to prevent the ingress of materials being conveyed into the adjacent bearing.

13. Apparatus for conveying pulverulent material, which comprises the combination of a casing having an opening at one end for the admission of material and an opening at the other end for the discharge thereof, a shaft having a portion lying within the casing, said portion being provided with a conveyor screw, a motor having a frame attached to the casing near one end thereof, the rotor of the motor being connected to the shaft, spaced bearings for the shaft, one at each side of the rotor, said bearings being mounted in the frame, the bearing remote from the casing being a radial and thrust bearing.

In testimony whereof I affix my signature.
JOSEPH H. MORROW.
